(57) **CLAIM**

The ornamental design for a beverage container cap, as shown and described.

DESCRIPTION

FIG. 1 is a top, front, left perspective view of a beverage container cap showing our new design.

FIG. 2 is a top, front, left perspective view of the beverage container cap of FIG. 1, shown in an alternate configuration for clarity of disclosure.

FIG. 3 is a front elevation view of the beverage container cap of FIG. 1.

FIG. 4 is a rear elevation view thereof.

FIG. 5 is a right-side elevation view thereof.

FIG. 6 is a left-side elevation view of the beverage container cap of FIG. 1, shown in condition for use.

FIG. 7 is a top plan view of the of the beverage container cap of FIG. 1; and,

FIG. 8 is a bottom plan view thereof.

The broken lines in the drawing depict portions of the beverage container cap that form no part of the claimed design. Additionally, in FIG. 6, the broken line showing a beverage container depicts environmental matter and forms no part of the claimed design.

The beverage container cap includes a cap which may be in a stowed position as depicted in FIGS. 1, 3, 4, 5, 6, and 7 or in an unstowed position as depicted in FIG. 2. The cap is not visible in FIG. 8.
